UNITED STATES PATENT OFFICE.

JOHNIE L. MORAN, OF CORNING, CALIFORNIA

STORM-RUBBER.

1,116,462.

Specification of Letters Patent. Patented Nov. 10, 1914.

Application filed July 23, 1913. Serial No. 789,790.

To all whom it may concern:

Be it known that I, JOHNIE L. MORAN, a citizen of the United States, residing at Corning, in the county of Tehama, State of California, have invented certain new and useful Improvements in Storm - Rubbers; and I do hereby declare the following to be a full, clear, and exact description of the invention, such as will enable others skilled 10 in the art to which it appertains to make and use the same.

This invention relates to storm rubbers and has for an object to provide a means for reinforcing the edge of the rubber upper and storm flap so as to make the same 15 hug the wearer's foot closely.

A further object of the invention is to provide a single reinforcing wire which is run around the marginal edge of the rubber 20 upper and storm flap but has the ends spaced considerably apart at the tip edge of the flap so that the latter may stretch over the wearer's instep without discomfort to the wearer.

With the above objects in view the invention consists of certain novel details of construction and combination of parts herein-after fully described and claimed, it being understood that various modifications may 25 be made in minor details of construction within the scope of the appended claim.

In the accompanying drawing illustrating this invention:—Figure 1 is a perspective view showing a storm rubber embodying 30 my improvements. Fig. 2 is a cross sectional view on the line 2—2 Fig. 1. Fig. 3 is a detail perspective view of the reinforcing wire.

Referring now to the drawing in which 35 like characters of reference designate similar parts, 10 designates an ordinary storm rubber having a storm flap 11 adapted to engage over the wearer's instep. For reinforcing the marginal edge of this storm rub-

ber and promoting the same hugging the 45 wearer's foot snugly, I provide a spring wire 12 of the general shape shown in Fig. 3, which wire is run around the edge of the rubber upper and storm flap as shown in Fig. 1, the free ends of the wire being 50 spaced considerably apart at the tip of the storm flap as shown at 13 whereby this flap may stretch to conform comfortably to the wearer's instep without obstruction from the reinforcing wire. The wire may be inserted 55 in the edge of the rubber in any suitable manner, and in the present embodiment of the invention the edge of the rubber is shown turned over the wire as at 14, and then cemented or otherwise secured to retain the wire in position. Any other manner of securing the wire in place may be employed without departing from the spirit or sacrificing any of the advantages of the invention.

From the above description it will be seen that I have provided an extremely simple and inexpensive device for reinforcing the marginal edge of the rubber upper and storm flap and promoting of the same hugging the wearer's foot comfortably.

What is claimed, is:—

The combination with a storm rubber having a storm flap of a single length of spring wire run around the upper marginal edge of the rubber upper and storm flap with the free ends spaced considerably apart at the tip of the storm flap whereby the latter may stretch to conform comfortably to the wearer's foot, said wire reinforcing said marginal edge and causing the same to hug the wearer's foot snugly.

In testimony whereof, I affix my signature, in the presence of two witnesses.

JOHNIE L. MORAN.
